UNITED STATES PATENT OFFICE.

JOHN W. BERCAW, OF HAMILTON, OHIO, ASSIGNOR TO THE AMERICAN LAUNDRY MACHINERY COMPANY, OF CINCINNATI, OHIO, A CORPORATION OF OHIO.

AUTOMATIC APRON-GUIDE ROLL.

Application filed September 10, 1920. Serial No. 409,443.

To all whom it may concern:

Be it known that I, JOHN W. BERCAW, a citizen of the United States, residing at Hamilton, in the county of Butler and State 5 of Ohio, have invented certain new and useful Improvements in Automatic Apron-Guide Rolls, of which the following is a specification.

This invention relates to improved means 10 for automatically correcting the side-wise movement of a web or belt, as for instance an apron in a flat work ironing machine.

It is the object of my invention to provide 15 an improved self-adjusting guide roll, in which the adjustment is effected by the creeping of the apron across the machine.

A further object of my invention is to provide means for automatically adjusting 20 one of the apron rolls, which means is actuated by the creeping of the apron along the same roll which is adjusted, so as to increase the sensitiveness, accuracy and dependability of the same.

Other objects will appear from the following description and claims when considered together with the accompanying drawings.

Fig. 1 is a vertical longitudinal sectional view of an ironing machine embodying my 30 invention; Fig. 2 is an end view of one end of an adjustable roll showing its pivot bearing; Fig. 3 is an end view of the other end of an adjustable roll showing the oscillatory bearing; Fig. 4 is a horizontal section on line 35 *a—a* Fig. 1; Fig. 5 is a vertical longitudinal section of the mounting of a guide roll taken on line *b—b*, Fig. 4; and Fig. 6 is a detail view of the oscillatory bearing taken on line *c—c*, Fig. 4.

The type of ironing machine here illustrated is well known in the art and comprises the metal steam chest 1, the padded rolls 2, 3, 4, 5 and the endless aprons 6 and 7. Apron 6 is driven by roll 8 and passes about 40 the idlers 9, 10 and 11. Apron 7 is driven by roll 12 and passes about other idlers 13, 14, 15 and 16. The apron 6 passes along the glazed under face of the steam chest and the two aprons pass in contacting relation between idlers 9 and 8. The arrows on the drawings indicate the direction of travel of the aprons. In operation the work is fed between the padded roll 5 and the steam chest and passes to the left, as viewed in

Fig. 1. It then passes to the right between the apron 6 and the under face of the steam chest, is carried to the left between the aprons 6 and 7 and is finally discharged from the apron 7 over the idler 16 onto a table which is generally employed at this point.

Considerable difficulty has been experienced with this type of machine because of the creeping of the apron back and forth across its path of travel, with the consequent 65 damaging of the apron and loss of time incident to the necessary stopping of the machine. This condition is relieved by the present invention in which the lateral creeping of the apron automatically effects proper 70 adjustment of the idlers 9 and 14. The mechanism here employed for adjusting the idlers 9 and 14 is the same in the two cases and a description of the one will therefore suffice. 75

The roll 14 has its gudgeon 17 at one end mounted in the bearing 18 which is adjustably mounted upon the horizontal rod 19. The collars 20 and 21 secure the gudgeon 17 in its bearing and a set screw is provided 80 for locking the bearing 18 in adjusted position. With this adjusting means it is possible to set the roll at the proper angle with respect to the edge of the apron according to conditions and as experience may dictate. 85 The rod 19 is carried by the bracket 22 which is swiveled at 23 upon the bracket arm 24 of the frame 25. The other end of the roll 14 is provided with a gudgeon 26 which is mounted in the bearing 27. A cone-shaped pulley 28 is formed on the bearing 27 for engagement by the edge portion of the apron as it creeps toward this side of the machine. The bearing 27 carries also a pinion 29 which engages the rack 30 on the 95 upper bracket member 31. The upper bracket member 31 is connected to the lower bracket member 32 by means of tie bolts 33. These bracket members are formed with horizontal tracks 34 and 35, respectively, for the upper and lower sets of rollers 36 and 37 which are journaled within the guide ways as at 39 formed on the bearing 27. The lower bracket member 32 is swiveled in the arm 40 on the frame 25. A lug 41 fast on bearing 27 has its outer end pivotally connected to the rod 42 which has its other end pivotally connected to one arm of bell-crank

lever 43. This lever 43 is mounted on the frame of the machine and carries a weight 44, which tends to draw the bearing 27 in a rearward direction, that is, to the left as viewed in Fig. 1. Because of the curvature of the apron about the roll 14, the adjustment of the roll to the right, as viewed in Fig. 1, will cause it to engage the inclined stretch of the apron, and the same is true of the roll 9, as will be seen from the drawing.

From the above it will be seen that the weight 44 tends to turn the roll 14 at an angle with respect to the length of the apron; with the result that the apron creeps toward the left as viewed in Fig. 5, since the apron has a natural tendency to shift toward the end of the roll that is rearwardly disposed along the path of travel of the apron. The apron will then engage the cone pulley and cause actuation of the pinion which by engagement with the rack will cause this end of the roll to be moved forwardly along the general path of the apron and to engage the inclined stretch of the apron. As soon as the roll 14 passes the position in which it bears an angle of 90° to the direction of travel of the apron, or in other words, when the end of the roll corresponding to bearing 27 becomes the advanced end, the apron will begin to shift toward the other side of the machine and will leave the cone-shaped pulley. Then the roll is again under the influence of the weight, as above explained. Thus it will be seen that the weight causes the bearing 27 to swing rearwardly while the operation of the rack and pinion causes this end of the roll to swing forwardly, with the result that the apron is prevented from creeping in either direction to any serious extent.

By having the creeping of the apron along a roll to operate through a direct connection to adjust the same roll, my device responds more quickly and the correction is more accurate and dependable than with other such devices. Furthermore, my device is simple in structure and is not apt to get out of order in service.

Other advantages will suggest themselves to those who are familiar with the art to which my invention relates.

What I claim is:

1. An apron control mechanism, comprising a guide roll, a pivotally mounted support for one end of said roll, said roll having a bearing that is mounted for manual adjustment upon the support at said one end thereof and a bearing that is mounted for automatic adjustment in the same plane at the other end thereof, means for effecting automatic adjustment of the roll angularly with respect to the apron, and means carried by said last named bearing for engagement by the apron for controlling the operation of said automatically adjustable means.

whereby the creeping of the apron across its path of travel is automatically corrected.

2. An apron control mechanism, comprising a guide roll, supports for the ends of said roll, said supports having pivotal movement in the same plane, said roll having a bearing that is mounted upon the support at one end thereof and a bearing that is mounted for automatic adjustment upon the support at the other end thereof, means for effecting automatic adjustment of the roll angularly with respect to the apron, and means carried by said last named bearing for engagement by the apron for controlling the operation of said automatically adjustable means, whereby the creeping of the apron across its path of travel is automatically corrected.

3. An apron control mechanism comprising a guide roll, a pivotally mounted support at one end of said roll, said roll having its one end mounted upon said support for adjustment lengthwise of the apron, the other end of the roll having a bearing that is mounted for oscillatory movement along the apron, means for automatically adjusting said oscillatory bearing, including means carried by said bearing for engagement by the apron for controlling the operation of said automatic adjusting means, whereby the creeping of the apron across its path of travel is automatically corrected.

4. An apron control mechanism comprising a guide roll, pivotally mounted supports for the ends of the roll, said roll having a bearing that is mounted for manual adjustment upon the support at one end thereof and a bearing that is mounted for automatic straight, line adjustment upon the support at the other end, means for effecting automatic adjustment of the roll angularly with respect to the apron, and means carried by said last-named bearing for engagement by the apron for controlling the operation of said automatic adjusting means, whereby the creeping of the apron across its path of travel is automatically corrected.

5. An apron control mechanism comprising an adjustable guide roll, said roll having a bearing at one end that is mounted for oscillatory movement along the apron, a guide-way allowing oscillatory movement of the said bearing therein, rollers between said bearing and guideway, means for adjusting said bearing including rack and pinion mechanism between said bearing and guideway and means carried by said bearing for engagement by the apron for controlling the operation of said adjusting means, whereby the creeping of the apron across its path of travel is automatically corrected.

In testimony whereof I hereby affix my signature,

JOHN W. BERCAW.
